UNITED STATES PATENT OFFICE

99,132

DESIGN FOR A BUILDING SIDING

Robert S. Maclean, Michigan City, Ind., assignor
to Mastic Asphalt Corporation, a corporation of
Indiana

Application August 28, 1935, Serial No. 58,332

Term of patent 14 years

To all whom it may concern:

Be it known that I, Robert S. Maclean, a citizen
of the United States, residing at Michigan
City, in the county of La Porte and State of Indiana,
have invented a new, original, and ornamental
Design for a Building Siding, of which the
following is a specification, reference being had
to the accompanying drawing, forming a part
thereof.

In the drawing:

Fig. 1 is a side elevational view of a section

of building siding showing my new design. Fig.
2 is a front perspective view of one of the units,
of which the building siding shown in Fig. 1 is
composed with a corner cut away for the purpose
of showing the structural contour of the unit.
Figure 3 is a section on the line 3—3 of Figure 2.

What I claim is:

The ornamental design for building siding, sub-
stantially as shown and described.

ROBERT S. MACLEAN.
